UNITED STATES PATENT OFFICE.

IRWIN W. HOWELL, OF NEWARK, NEW JERSEY, ASSIGNOR TO THE
GENERAL ELECTRIC COMPANY, OF NEW YORK.

DESIGN FOR A ROENTGEN-RAY TUBE.

SPECIFICATION forming part of Design No. 27,953, dated December 7, 1897.

Application filed August 26, 1897. Serial No. 649,649. Term of patent 14 years.

To all whom it may concern:

Be it known that I, IRWIN W. HOWELL, a citizen of the United States, and a resident of Newark, in the county of Essex, State of New Jersey, have invented and produced a new and original Design for Roentgen-Ray Tubes, of which the following is a description, reference being had to the accompanying drawing, in which I have represented in perspective my design.

The leading and material feature of my design is a main bulb A of the tube, with a tubular extension B, containing the cathode b and having a terminal E. The opposite side of the bulb is provided with another extension I, also having a terminal D, support-

ing an inclined piece C within the main body of the tube A. A tube II extends from the portion I of the main tube, and from the tube II extends another tube G, having a cap and terminal F.

Having thus described my invention, what I claim is—

The design for a Roentgen-ray tube as herein shown and described. 25

In witness whereof I have hereunto set my hand this 24th day of August, 1897.

IRWIN W. HOWELL.

Witnesses:

WM. H. MEADOWCROFT,
CLARENCE T. VAN DEREN.
